UNITED STATES PATENT OFFICE.

WILLIAM DURHAM SARGENT, OF CHICAGO, ILLINOIS.

BRAKE-SHOE.

SPECIFICATION forming part of Letters Patent No. 643,734, dated February 20, 1900.

Application filed August 17, 1899. Serial No. 727,501. (No model.)

To all whom it may concern:

Be it known that I, WILLIAM DURHAM SARGENT, a citizen of the United States, residing at Chicago, in the county of Cook and State 5 of Illinois, have invented certain new and useful Improvements in Brake-Shoes, of which the following is a specification.

This invention relates to improvements in brake-shoes, and has for its primary objects to prolong the life of the shoe, to afford a constant and practically uniform wearing-surface throughout the life of the shoe, and to provide a soft-cast-iron shoe with chilled portions so disposed that the transition from the 15 soft to the hardened metal will be gradual and not of a nature to injuriously wear the wheel, as has heretofore uniformly been the case. These and such other objects as may hereinafter appear are obtained by the devices illustrated in the accompanying drawings, in which—

Figure 1 represents a side elevation, partly in section, of a brake-shoe embodying my invention. Fig. 2 represents a perspective view 25 of one end thereof, showing the chill applied thereto.

Similar letters of reference indicate the same parts in both figures of the drawings.

Referring by letter to the accompanying 30 drawings, A indicates the body of the brake-shoe; B, prolongations at each end thereof; C, the chilled portions of the prolongations at each end of the shoe, (indicated by dotted lines at the upper end of the shoe,) and D the 35 chill for producing the chilled portions in the prolongations.

The dotted line E and E indicates the line 40 of termination of the body of the brake-shoe as ordinarily constructed, so that the portion B projecting beyond this line at each end of the shoe constitutes a prolongation of the shoe beyond what is ordinarily provided and affords a means for chilling the ends of the shoe from the back instead of from the front 45 and sides of the shoe. It will be noted that the chill D does not embrace the sides of the shoe nor extend around the wearing-face thereof, but makes contact only with the brake at the prolongations. While I have shown 50 the prolongation as generally triangular in shape, it may be square, rounding, or of any

other desired contour. The chill is set into the mold and the shoe is cast, that portion opposing the chill being hardened from the back inwardly toward the bottom of the shoe, 55 but not extending to the wearing-face thereof, the intention being to leave about three-sixteenths of an inch of soft cast-iron—say from the line a a to the wearing-face of the shoe—between the chilled portion and the wearing- 60 face, so that when the shoe is first put in service there will be no contact with the wheel of the chilled portion of the metal until this soft-iron facing is worn down and the wearing-face of the shoe conforms to the arc 65 of the wheel-tread. As will be seen, however, during the wear of the shoe from the point a a to the point b b the area of chilled metal exposed on the wearing-face of the shoe will be substantially uniform, and this uniformity will continue throughout the life of the shoe, as will be readily seen by an examination of Fig. 1, which shows with approximate correctness the area of the chilled portion at the successive points indicated by 70 the lines c c, d d, and e e.

The chill which is produced by hardening from the back of the end of the shoe is of an entirely-different character from that which is produced by hardening the face of the shoe 80 at the end or at any point intermediate to the ends. In the case of my shoe the area of chilled metal at each end of the shoe in contact with the wheel is practically uniform throughout the life of the shoe after the soft- 85 metal facing is worn away, and the chill coming from the back of the shoe, causing the greatest density immediately on the back face of the shoe, with gradually-decreasing density as the chill penetrates the shoe, is not of a 90 nature to injuriously wear the wheel, whereas in the case of shoes having chilled parts made from the wearing-face of the shoe inwardly the area of the chilled section is far greater at the commencement of wear and greatly 95 diminishes as the shoe is worn, while the chill is hardest at the wearing-face of the shoe and of a character calculated to injuriously wear the wheel.

Practically the entire body portion of my 100 shoe coming in contact with the wheel is an area of soft cast-iron, and the area in contact

with the wheel at the commencement of service is the same as the Master Car-Builders' standard cast-iron shoe.

My aim is to take a soft-cast-iron brake-
5 shoe and add metal at the ends which may be
so hardened from the back as to prolong the
life of the shoe without injuriously affecting
the wheel or diminishing the frictional power
of the shoe. Of course, as before stated, the
10 metal that is added to the end of the shoe may
be either shaped as in the drawings or it may
be rounded or squared, so long as the essential
feature is retained—that of its being chilled
15 or hardened from the back, so that the chill
merges into the soft cast-iron before reaching
the surface of the shoe exposed to wear
against the wheel in commencing service.

While I have shown in the drawings the
prolongations as extending tangentially to the
20 tread of the wheel, it is within the contemplation
of my invention to form this extension concentric
with the tread of the wheel, if desired, though the form shown in the drawings
is preferred, because in the commencement
25 of service the area of contact between
the shoe and the wheel is the same as the
standard cast-iron shoe.

My invention possesses numerous advantages
30 over any prior form of chilled-cast-iron
shoe known to me, especially as regards the
strength of construction due to the fact that
the entire body of the shoe is composed of
soft and strong iron and the chilling of the
35 prolongations at the ends does not in any way
diminish the strength of the shoe, but rather
by increasing the density of the metal inside
of and contiguous to the chilled portion adds
to the strength of the shoe. This I have demon-
strated by tests. Furthermore, I have

found that it is possible by chilling from the 40
back to obtain greater uniformity, from the
fact that all of the surface of the shoe, as
stated above, is of soft cast-iron until the shoe
has suffered a wear of about three-sixteenths
45 of an inch, while in all other forms of shoes
containing chilled sections there is either a
portion of the chilled surface in contact with
the wheel at the outset or the area of soft
50 cast-iron in contact with the wheel constitutes
only a part of the Master Car-Builders' stand-
ard area for shoe-surface. With the character-
istics of durability obtained from the
55 chilled portion of my shoe I have greater
strength, more friction, and greater uniform-
ity of action on the wheel than any other
chilled shoe, and all of these results arise from
chilling the back of the prolongation on each
end of the shoe.

Having described my invention, what I
claim, and desire to secure by Letters Patent, 60
is—

1. A cast-iron brake-shoe having triangular
prolongations tapering from the back to the
wearing-surface of the shoe at the ends thereof
and chill-hardened from the back, said 65
chilled portions not extending to the wearing-
surface of the shoe, substantially as and for
the purpose described.

2. A cast-iron brake-shoe having tangential
triangular prolongations at the ends thereof 70
chill-hardened from the back, said chilled por-
tions not extending to the wearing-face of the
shoe, substantially as and for the purpose de-
scribed.

WILLIAM DURHAM SARGENT.
